UNITED STATES PATENT OFFICE.

GURDON H. WILLIAMS, OF GREENSBURG, OHIO.

END-GATE FOR WAGONS.

SPECIFICATION forming part of Letters Patent No. 314,407, dated March 24, 1885.

Application filed August 26, 1884 (No model.)

To all whom it may concern:

Be it known that I, GURDON H. WILLIAMS, of Greensburg, in the county of Trumbull and State of Ohio, have invented certain new and useful Improvements in End-Gates for Wagon-Boxes; and I do hereby declare the following to be a full, clear, and exact description of the invention, such as will enable others skilled in the art to which it pertains to make and use

10 the same.

My invention relates to improvements in end-gates for wagon-boxes; and it consists in certain features of construction and in combination of parts hereinafter described, and

15 pointed out in the claim.

In the accompanying drawings, Figure 1 is a plan view of the end-gate closed, and shows also the adjacent parts of a wagon-box. Fig. 2 is a plan view of the same, showing the 20 end-gate partially opened. Fig. 3 is a rear view in elevation of the end-gate. Fig. 4 is a side view in elevation of the plate. Fig. 5 is a view in perspective of the part F.

A represents the sides and B the bottom of 25 the wagon-box. The side-boards are provided, in the usual manner, with the cleats a, that, when the parts are in position, embrace the ends of the end-gate. A rod, a', passes through the side-boards in the usual manner, 30 and prevents these boards from spreading.

The end-gate is double or of two boards in thickness, and the inner part consists of the pieces C and C', that are hinged together at c. The outer part consists of the pieces D and 35 D', that join on the oblique line d, and the former is rigidly attached to the inner part, C, and the latter is attached to the part C' and overlaps some distance on the part C. Vertical cleats d' are secured on the outside in the position 40 shown, that prevent the end-gate from splitting. To the part D' is secured the broad plate E, that overlaps the joint and extends some distance onto the part D. This plate on the overlapping part has transverse slots 45 e, through which the staples or eyebolts e' protrude, that are secured to the parts D and C.

F is a plate bent in the form shown in Fig. 5, and provided with the slots f, and with rounded ends forming pins f'. The part F is secured

50 to the plate E by bolts or rivets that pass through the elongated holes f, by means of which the part F may be slid up or down as far as the elongated holes will permit. When the part F is elevated, the pins f' are above the center of the slots e, and when depressed 55 the pins f' pass through the protruding ends of the staples or eyebolts e' and lock the end-board.

The parts D and D' are of such length that they fit snugly between the cleats a of the 60 side-boards, and the parts C and C' are of such width that they slide under the rod a', and the end-gate is thus held from rising. By raising the part F the pins f' are disengaged 65 from the eyebolts or staples e, and by drawing the center part of the end-gate rearward, as shown in Fig. 2, the end-gate is disengaged from at least one side-board, and may be easily removed and as easily returned to its position and locked.

70 The device is cheap, simple, and durable, and will be found a convenient end-gate for all ordinary purposes.

What I claim is—

An end-gate for a wagon-box, consisting of 75 the parts C and C', of unequal length and hinged together, and of such width as to slide under the rod a', and the outside pieces, D and D', joined, respectively, to the inner parts, and so arranged as to break joints, in the manner 80 shown, and the plate E, secured to the part D and overlapping the joint, and provided with the slots e, arranged to admit the staples or eyebolts e', and the part F, bent in the manner shown, and provided with the slots f and 85 the rounded ends or pins f', and so arranged and secured to the plate E that the part F may be depressed and the pins f' caused to engage the part e' and lock the end-gate, substantially as set forth.

90 In testimony whereof I sign this specification, in the presence of two witnesses, this 4th day of August, 1884.

GURDON H. WILLIAMS.
